P. J. HORGAN.

FASTENER SETTING MACHINE.
APPLICATION FILED MAY 11, 1918.

1,388,862.

Patented Aug. 30, 1921.

UNITED STATES PATENT OFFICE.

PATRICK J. HORGAN, OF BEVERLY, MASSACHUSETTS, ASSIGNOR TO UNITED SHOE MACHINERY CORPORATION, OF PATERSON, NEW JERSEY, A CORPORATION OF NEW JERSEY.

FASTENER-SETTING MACHINE.

1,388,862.

Specification of Letters Patent. Patented Aug. 30, 1921.

Application filed May 11, 1918. Serial No. 233,870.

To all whom it may concern:

Be it known that I, PATRICK J. HORGAN, a citizen of the United States, residing at Beverly, in the county of Essex and State of Massachusetts, have invented certain Improvements in Fastener-Setting Machines, of which the following description, in connection with the accompanying drawings, is a specification, like reference characters on the drawings indicating like parts in the several figures.

This invention relates to fastener setting machines and, in some of its aspects, it is particularly concerned with machines for setting compound or two-part fasteners such as gromets and washers, or the like. It will be understood, however, that, while a particular machine specially designed for setting a particular fastener will be herein specifically described, certain features of the invention are equally adapted for use in other types of machines and with other types of fasteners.

One type of machine which has been very extensively employed for inserting single fasteners, one at a time, is illustrated in Letters Patent of the United States No. 898,729, granted September 15, 1908, upon an application of J. F. Davey, and embodies coöperating sets arranged in vertical alinement, with the upper set stationary and the lower set capable of movement toward and away from the upper set. The fasteners are supplied to the lower set by means of a movable raceway which is oscillated into and out of alinement with the lower set. In certain cases, however, it becomes desirable to deliver a fastener to the upper set, as when a raceway delivering fasteners to the lower set would interfere with the work and as, in the illustrative case, when it is desired to use the machine for setting compound or two-part fasteners so that one part of the fastener must be delivered to the lower set and the other part of the fastener to the upper set for coöperating engagement with the two sides of the work.

An object of the invention is to provide improved means for delivering fasteners from a raceway to a stationary upper set.

An important feature of the invention relates to the manner in which the spindle of the upper set and the raceway coöperate to deliver fasteners successively to the set.

Other features of the invention relate to the operating mechanism for the lower set and the raceway operating mechanism.

These and other features of the invention will be best understood by considering the particular machine designed for setting gromets and washers which is described in the following specification and shown in the accompanying drawings, in which,—

Figure 1 is a side elevation of the machine with parts in section;

Fig. 2 is an angular view of the coöperating sets and the ends of the two raceways;

Figs. 3, 4, 5 and 6 are transverse sections of the sets showing their relation in various positions and the relation of the raceways thereto.

A frame 10 has journaled therein a driving shaft 12 which will be provided with any suitable driving or controlling mechanism, not shown herein, and preferably including a single-revolution clutch. The forward portion of the frame will preferably be recessed at 14 for the reception of work and above this recess there is mounted in fixed position an upper set 16 which may be retained in the frame by means of a clamping bolt 18 which preferably engages a notch in the set. Slidably mounted within this set is a spindle 20 adapted to be normally urged downwardly as, for example, by means of a spring 22. Yieldable spindles of the sort thus far described are well known in the art and are commonly adapted to thread an annular fastener and frictionally to retain the same in position adjacent to the set. In order, however, for a fastener to be positioned upon the spindle, it is necessary that the spindle and the associated raceway shall at some time be in intersecting relation, but when the raceway is advancing to carry the leading fastener into alinement with the spindle some provision is necessary to prevent interference between the spindle and the fastener. Accordingly for the purposes of the present invention the upper end of the spindle is preferably provided with a head 23 which limits the downward movement of the spindle, and this head has an overhanging crown 24 for engagement with one arm of a pivoted latch 26 which is normally held toward the line of the spindle by means of a spring 28. When the spindle is retracted, as illustrated in Fig. 5, the latch underlies the rim

of the crown, and the spindle is thus locked in retracted position. Fasteners are supplied to the upper set 16 from a curved raceway 30 pivotally mounted at 32 upon the frame 5 and carrying at its upper end a hopper 34 of any suitable form. Preferably, these parts will be so designed that their center of gravity is approximately at the pivot point in order to reduce their inertia and lessen the vibration 10 of the machine. The lower end of this raceway will be provided with the usual retaining spring and the raceway is so designed that the lowermost fastener therein may be brought into alignment with the set 15 16 and the spindle 20 by the pivotal movement of the raceway. In order to prevent interference between the raceway and the spindle 20, the spindle is retained in retracted position by means of the latch 26 20 until the lower end of the raceway has moved into alignment with the spindle 20. The spindle is then released for downward movement by engagement of the latch 26 with a roller 36 upon the raceway 30. The relative 25 position of the parts just before the spindle is released is shown in Fig. 6. It is intended that the upper raceway in the particular embodiment of the invention herein illustrated shall be used for gromets and it will be noted 30 that the design of the raceway is such that these gromets are delivered from the hopper with their barrels up and are reversed during movement of the raceway so that they may be applied flange up to the upper 35 surface of the work.

The lower set 40 is resiliently supported upon a stiff spring 42 in a slide 44 guided in the frame 10 for vertical movement in alignment with the upper set. Upward movement of the lower set 40 with relation to said 40 slide 44 is limited by means of a bolt 46. Surrounding the lower set 40 and adapted to assist in centering a washer with relation to the said set and its centrally projecting portion is a sleeve 48 pressed outwardly by means of a spring 50 (see Fig. 3) and limited in its movement by means of a pin and slot connection 52 with the set 40. The side of this sleeve toward the raceway is beveled 45 in order gradually to release the same for upward movement after the washer has been delivered to the lower set by the washer-raceway. This washer centering device is particularly desirable because of the fact that 50 it is necessary for the central projection of the set 40 to be small enough to enter the barrel of the gromet, and hence to be smaller than the inside diameter of the washer. This device is shown and claimed 55 in Letters Patent of the United States No. 1,231,210, granted June 26, 1917, upon an application of Walter Shaw.

Reciprocation of the lower set is effected by means of a lever 60 pivoted upon the main

shaft 12 and connected by means of a slotted 65 end to a cross pin 62 in a slot of the slide 44. Actuation of this lever 60 is effected by power conveyed from the main shaft 12 through an eccentric 64 and a link 66 to a lever 68 which is pivoted at 70 upon the frame of the machine. One arm of this lever 68 is connected to the lever 60 by means of a toggle link 72 thus forming a very powerful and effectual arrangement for transforming the rotary motion of the shaft 12 into the reciprocating 75 motion of the slide 44.

Fasteners, in this case annular washers, are supplied to the lower set 40 from a raceway 74 which is practically straight throughout its entire length and is supplied with 80 washers by a hopper 76 of usual form carried at its upper end. The upper end of the raceway 74 is supported by means of a sliding T-slot connection to a member 78 which is pivotally mounted upon a rearward 85 extension of the lever 68. The forward end of the raceway is pivotally supported upon a link or lever 80 pivotally attached at 82 to the frame of the machine. Actuation of this raceway to deliver washers to the lower 90 set is effected by means of a pin 84 carried by the lever 60 so as to coat with a cam slot 86 in the lever 80. It will be noted that the construction and arrangement of the 95 parts for supporting and actuating the raceway 74 is such that when the forward end of the raceway is moved into alignment with the lower set to deliver a washer thereto, the rear end of the raceway is depressed so that the raceway assumes a more nearly horizontal position and the fastener is delivered to the lower set at a relatively high level. When the raceway is retracted so that it is out of delivering position, the rear end of the raceway is elevated, thereby facilitating the flow of washers along the raceway and depressing the delivery end of the latter so as to clear the work. A feature of utilizing the lever 68 to support the rear 100 part of the raceway is that it synchronizes the up and down movements of the delivery end with those of the lower tool 40 and insures that the delivery end and the tool will move in opposite directions relatively to each other. The upper or gromet raceway 30 is actuated in suitable timed relation to the other parts of the machine by means of a lever 88 pivotally mounted at 90 upon the frame of the machine and pivotally connected at its upper end to said raceway. 105 The actuation of this lever is effected in a similar manner to that of the lever 80 by means of a pin and cam slot connection with the lever 60.

The machine is preferably controlled so 115 that in its stop position the parts will assume the relation illustrated in Figs. 1, 2 and 3. It will be noted that a washer has

been delivered to the lower set and the washer raceway 74 has been retracted out of alinement with said set. The gromet raceway 30, on the other hand, supports the 5 leading gromet in alinement with the upper set and the spindle 20 is threading the gromet as shown best by Fig. 3. Rotation of the shaft will first cause the retraction of the upper raceway 30 and the gradual elevation of the lower set to cause the parts to 10 assume the position illustrated in Fig. 4. Assuming that the previously apertured work 100 has been placed on the projection of the lower set 40 the latter will lift the 15 work and the washer into coöoperative relation with the gromet, and will ultimately clench the gromet. At this time the projection upon the lower set 40 will have lifted the spindle 20 so that the crown 24 upon 20 the head of the spindle will be caught by the latch 26, as shown in Fig. 5. As the cycle continues the lower set will go down to its lowest position, the washer raceway will carry a new washer into alinement with 25 the lower set, the latter will rise to take the new washer, and the washer raceway will move back to the position illustrated in Fig. 1. At approximately the same time the upper raceway will be brought into alinement with the spindle 20 and, as illustrated 30 in Fig. 6, will release the spindle 20 to thread the lowermost gromet in said raceway by reason of the contact of the roller 36 with the latch 26. The machine will now 35 be ready for a repetition of its cycle upon the release of the one-revolution clutch by the operator.

Having thus described my invention, what I claim as new and desire to secure by Letters Patent of the United States is:

1. A fastener-setting machine comprising a stationary setting tool and a movable spindle extending therethrough, a raceway the delivery end of which is movable to 45 and from registration with said spindle to supply fasteners successively thereto, and means controlled by movement of said raceway to cause said spindle to function.

2. A machine of the class described having, in combination, a setting die, a spindle slidably mounted within said die, a raceway for annular fasteners mounted for movement to bring the endmost fastener in the raceway into and out of alinement with said 55 spindle, and means responsive to the movements of the raceway for controlling said spindle.

3. A machine of the class described having, in combination, a setting die, a spindle 60 slidably mounted within said die, means urging said spindle to its outermost position, a raceway for supplying fasteners to said spindle and die, adapted to be brought into and out of alinement therewith, means for

retaining said spindle in retracted position, 65 and means responsive to the movements of said raceway for controlling the operation of said retaining means.

4. A machine of the class described having, in combination, a setting die provided with a yieldable spindle, a raceway for supplying annular fasteners to said spindle movable into and out of alinement with the die and spindle and across the extended position of the spindle, a latch for retaining 75 said spindle in retracted position, and means responsive to the movement of said raceway for releasing said latch to allow said spindle to pass through the endmost fastener in the raceway.

5. A machine of the class described having, in combination, coöoperating sets, one of said sets being provided with a slidable spindle constructed and arranged to be normally in extended position, means comprising one of said sets for moving said spindle to retracted position, means for retaining said spindle in retracted position, a raceway for supplying fasteners to said spindle movable into and out of alinement therewith, and means responsive to the movement of said raceway for releasing said retaining means to allow said spindle to pass into extended position and engagement with a fastener in 95 said raceway.

6. A machine of the class described having, in combination, coöoperating setting dies, a spindle associated with one of said dies and relatively movable with respect to the die, said spindle and die being constructed and arranged so that the spindle is normally in extended position, raceways for supplying fasteners to the respective dies, there being provision for relative movement of a raceway and the spindle to bring the endmost 100 fastener in the raceway in alinement with the spindle, and means responsive to the relative movement of the spindle and raceway for controlling the relative movement of the spindle and die.

7. A machine of the class described having, in combination, coöoperating setting dies, a slidable spindle associated with one of said dies and constructed and arranged to be normally in extended position, raceways for 115 supplying fasteners to the respective dies, and means responsive to the movement of one of said raceways for controlling said slidable spindle.

8. A fastener-setting machine comprising a setting tool, an inclined raceway for supplying fasteners to said tool, and raceway-operating mechanism including two movable members arranged to support the raceway at different points along its length, one of 125 which members is arranged to move the adjacent portion of the raceway transversely to the length of the raceway and the other

- of which is arranged to move the raceway lengthwise to and from fastener-delivering position relatively to said tool.
9. A machine of the class described having, in combination, a raceway, pivoted links for supporting said raceway, one of which is pivotally connected thereto and the other of which is slidably connected to the raceway, and means for oscillating the raceway 10 constructed and arranged to cause said links to be oppositely rotated during any one progressive movement of the raceway.
10. A machine of the class described having, in combination, coöperating sets, raceways for supplying fasteners to the respective sets, a lever for reciprocating one of the sets, pivoted members for oscillating said raceway into and out of alinement with the sets, and cam connections between said lever 20 and said pivoted members for actuating the pivoted members to oscillate the raceways.
11. A machine of the class described having, in combination, a fixed set and a movable set, raceways for supplying fasteners to the respective sets, a slidable spindle associated with the fixed set, a lever for operating said movable set and the raceways, and means including said lever constructed and arranged to control the movements of the 30 slidable spindle.
12. A machine of the class described comprising coöperative setting members of which one is movable, a movable raceway for supplying fasteners to one of said setting members, a movable raceway-support, means arranged to reciprocate said support, and means operable by said support to operate the movable setting member so as to take a fastener from the raceway.
- 40 13. A machine of the class described having, in combination, a frame, a driving shaft journaled therein, a bell crank lever pivoted upon the frame, connections between said shaft and the lever for oscillating the same, coöperating dies, one of which is movable, a lever for moving said set journaled upon said shaft, and a toggle link connection between said bell crank lever and said set operating lever.
- 50 14. A machine of the class described comprising coöperative setting members one of which is movable, a movable raceway for supplying fasteners to one of said setting members, mechanism for operating the movable setting member, said mechanism including a reciprocatory member arranged to support the raceway and to move the latter, and means arranged to impart other movement to the raceway.
- 60 15. A machine of the class described comprising fastener-setting tools, a raceway for supplying fasteners to one of said tools, a movable raceway-support relatively to which the raceway is movable lengthwise, means for moving said raceway as aforesaid, and means 65 operable by the first said means for moving said raceway support transversely of the length of the raceway so as to cause a compound movement of the raceway.
16. A machine of the class described comprising fastener-setting tools, a raceway for supplying fasteners to one of said tools, a movable raceway-support relatively to which the raceway is movable, means for moving said raceway-support so as to vary the inclination of the raceway, and means operable by said support for moving the raceway relatively to the raceway-support so as to shift the delivering end of the raceway to and from delivering position.
- 70 17. A fastener-inserting machine comprising two coöperative setting tools, mechanism for reciprocating one of said tools toward and from the other, a raceway for supplying fasteners to said movable tool, mechanism arranged to move the raceway to and from fastener-delivering position relatively to said movable tool, and means arranged to move the delivery end of the raceway in synchronism with but in the opposite direction relatively to the reciprocatory movements of said movable tool.
- 75 18. A machine of the class described comprising an operating shaft, an operating member carried by the shaft, coöperative 80 setting tools, a raceway for supplying fasteners to one of said tools, and mechanism operable by said operating member and including two relatively movable members connected to and supporting separate portions of the raceway, each of said two members being arranged to reciprocate the raceway otherwise than along the lines of reciprocation pertaining to the other.
- 90 19. A machine of the class described comprising an operating shaft, an operating member carried by the shaft, coöperative setting tools, a raceway for supplying fasteners to one of said tools, and mechanism operable by said operating member and including a member arranged to operate one of the setting tools, and including two other members connected to and supporting separate portions of the raceway, each of the two latter members being arranged to reciprocate the raceway otherwise than along the lines of reciprocation pertaining to the other of said two members.
- 100 20. A machine of the class described comprising coöperative setting tools one of which is provided with a relatively movable central spindle, a movable raceway arranged to supply fasteners to said spindle, means for moving the raceway so as to shift the delivery end thereof to and from registration with the spindle, and means arranged to operate the spindle in conjunction with the raceway so as to remove the leading fas-
- 105 110 115 120 125

tener from the raceway while the setting tool with which the spindle is associated remains still.

21. A machine of the class described comprising coöperative setting tools, one of which is stationary, a raceway for supplying fasteners to the stationary tool, means arranged to move the raceway so as to shift the delivery end thereof to and from alignment with the setting tools, and movable means telescopically related to the stationary tool and operable to remove a fastener from the raceway.

22. A machine of the class described comprising coöperative setting tools, a raceway for supplying fasteners, means arranged to operate the raceway so as to shift the delivery end thereof to and from registration with the setting tools, and means controlled by the raceway so as to remove a fastener from the latter in registration with the setting tools.

23. A machine of the class described comprising upper and lower setting tools, a movable raceway for supplying fasteners to the upper setting tool, and means operable independently of movement of the upper tool to remove a fastener from the raceway and to support the fastener by its internal surface between the upper tool and the plane of the work.

24. A machine of the class described comprising setting mechanism including a fixed setting tool, a movable raceway arranged to supply fasteners to the fixed tool, and movable means arranged in said fixed tool to remove a fastener from the raceway in proximity to the fixed tool.

25. A machine of the class described comprising setting mechanism including a fixed setting tool, a movable raceway arranged to supply fasteners to the fixed tool, and means controlled by the raceway so as to remove a fastener therefrom in registration with the fixed tool.

26. A machine of the class described comprising setting mechanism including a fixed setting tool and a spindle arranged centrally therein, a movable raceway arranged to supply fasteners to the fixed tool, and means arranged to operate said spindle so as to remove a fastener from the raceway.

27. A machine of the class described comprising setting mechanism including a fixed setting tool and a movable spindle therein, a movable raceway arranged to supply fasteners to said tool, and means controlled by the raceway to cause said spindle to remove a fastener from the raceway.

28. A machine of the class described comprising setting mechanism including a fixed setting tool and a movable setting tool, a raceway for supplying fasteners to the fixed tool, the delivery end of the raceway being

movable to and from registration with the fixed tool, a spring-projected spindle arranged in the fixed tool so as to be pushed back by the movable tool, and means arranged to restrain the spindle when the latter is pushed back, said means being controlled by the raceway so as to release the spindle when the end of the raceway is in registration with the fixed tool, the spindle being thereupon movable under the influence of its projecting spring to thread the fastener at the end of the raceway.

29. A machine of the class described comprising setting mechanism including an upper setting tool and a lower setting tool, a raceway for supplying fasteners to the upper tool, the delivery end of the raceway being movable to and from registration with the upper tool, a spring-projected spindle arranged in the upper tool so as to be pushed back by the lower tool, and means arranged to restrain the spindle when the latter is pushed back, said means being controlled by the raceway so as to release the spindle when the end of the raceway is in registration with the upper tool, the spindle being thereupon movable under the influence of its projecting spring to thread the fastener at the end of the raceway.

30. A machine of the class described comprising an upper setting tool, a lower setting tool, mechanism for operating the lower tool, a movable raceway arranged to supply fasteners to the upper tool, a spindle associated with the upper tool to coöperate with the raceway, and means operable by said mechanism to operate the raceway and to control the movements of said spindle.

31. In a machine of the class described, a movable raceway, and setting mechanism including a movable setting tool, another setting tool, a spindle associated with the latter and movable relatively thereto by the said movable setting tool, and means controlled by the raceway and arranged to insert the spindle through a fastener in the raceway.

32. In a machine of the class described, a movable raceway, and setting mechanism including a movable setting tool, a fixed setting tool, a spindle associated with the fixed tool and movable by the movable tool, and means under control of the raceway for inserting the spindle through a fastener in the raceway.

33. A machine of the class described comprising a movable raceway, and setting mechanism including upper and lower setting tools, a spindle associated with the upper tool and movable relatively thereto by the lower tool, and means under control of the raceway for inserting the spindle through a fastener in the raceway.

34. A fastener-inserting machine compris-

ing coöperative setting tools one of which is movable toward and from the other, mechanism including a reciprocatory member for reciprocating said movable tool to set fasteners, a raceway for supplying fasteners to said movable tool, and means arranged to move the raceway to and from registration with said movable tool, the raceway being supported in part by said reciprocatory

member so that the latter will move the delivery end of the raceway relatively to said movable tool and in the opposite direction to carry a fastener over the end of the tool and then toward the tool. 10

In testimony whereof I have signed my 15 name to this specification.

PATRICK J. HORGAN.
